UNITED STATES PATENT OFFICE.

WILLIAM TATE BRADLEY, OF TROY, ALABAMA.

RAIL-JOINT.

1,224,844.

Specification of Letters Patent.

Patented May 1, 1917.

Application filed January 19, 1917. Serial No. 143,342.

To all whom it may concern:

Be it known that I, WILLIAM T. BRADLEY, a citizen of the United States, residing at Troy, in the county of Pike and State of Alabama, have invented new and useful Improvements in Rail-Joints, of which the following is a specification.

The present invention relates to improvements in means for connecting the meeting 10 ends of two railway rails.

In carrying out my invention it is my purpose to cut the confronting ends of two ordinary railway rails horizontally and angularly from the top to the base of said 15 rails whereby the angular end of one of the rails will overlie the angular end of the other rail and to provide a chair member in the nature of a cuff designed to be arranged upon the rails at the meeting ends 20 thereof and to be secured to the meeting ends, whereby to effectively connect the ends.

It is a further object of the invention to produce a rail joint having lapping ends 25 whereby one of the rails at the end thereof will support the other rail, to provide a chair member which is designed to be arranged upon one of the rails at the end thereof and to be moved over the other rail 30 to lap both of the rails, and to pass through the sides of the chair and through the webs of the rail staggered connecting elements, certain of the said openings receiving the 35 said elements being elongated in a horizontal direction whereby to permit of the expansion and contraction of the rails and at the same time aid the chair member in supporting the rail ends, and whereby the said rail ends will be prevented from movement 40 in a vertical or tilting direction.

It is a still further object of the invention to produce a rail joint which shall be of an extremely simple construction, cheap to manufacture and which will effectively 45 and securely support the meeting ends of the rails.

With the above and other objects in view the improvement resides in the construction, combination and arrangement of parts 50 set forth in the following specification and falling within the scope of the appended claim.

In the drawing:

Figure 1 is a perspective view illustrating 55 the application of the improvement,

Fig. 2 is a transverse sectional view approximately on the line 2—2 of Fig. 1, and

Fig. 3 is a vertical longitudinal sectional view through the chair and the connecting bolts, the rails being shown in elevation.

Referring now to the drawing in detail, the numerals 1 and 2 designate two rails of the ordinary construction. Each of these rails at the end thereof is cut angularly from the top to the bottom thereof whereby the head of the rail 1 is projected beyond the base of the said rail and the base of the rail 2 is extended beyond the head of the rail. These angular ends of the rails are designed to engage one another so that one of the said rails will have a tendency to support the other rail at the ends of the rails. The rails are supported upon suitable ties 4, and the numeral 5 designates the joint chair member for the rail ends. The joint chair includes a flat base 6 which receives the base of the rails 1 and 2 and angular sides 7—7 which have their inner faces shaped to conform to the sides of the rails, the said sides being received in the fishing spaces of the rails. The sides of the chair member are provided with staggered elongated slots 9 which register with similarly staggered openings 10 in the webs of the rail. The slots are disposed horizontally and passing through the alining slots and openings in the chair member and rail are the ordinary bolts 12 that are secured by the usual nuts 13. The edges of the joint chair are preferably notched whereby to receive spikes 14 that enter the ties.

The joint chair, it will be noted, is in the nature of a cuff and in application the same is inserted over the end of one of the rails and moved longitudinally and inwardly of the said rail. When the second rail is brought to have its end receive the end of the first referred to rail, the cuff member or chair is moved outwardly to embrace the referred to first mentioned rail, and thereafter the securing elements are passed transversely through the referred to slots in the sides of the chair and the webs of the rails. After the nuts have been applied to the bolts the spikes are inserted through the notches in the edges of the chair as above set forth.

By arranging the slots longitudinally in the sides of the chair it will be noted that the bolts not only serve as an auxiliary sup-

porting means for the rails but also permit of the expansion and contraction of the said rails.

Having thus described the invention,
5 what I claim is:

The herein described means for connecting the meeting ends of rails including two rails having their ends cut angularly from the head to the base thereof, whereby the
10 base of one of the rails will be extended beyond the head thereof and the head of the other rail projected beyond the base thereof, said cut ends adapted to rest one upon the other, the webs of the rails having staggered
15 openings, a chair member including a

base and angular sides formed with the base and the rails adapted to rest upon the base of the said chair, the sides of the chair adapted to be received in the fishing spaces of the rail, the sides of the chair having horizontally disposed elongated staggered openings registering with the openings in the webs of the rails, securing means passing through the said openings, ties upon which the rails and chair rest, and securing elements passing through notches in the edges of the chair and entering the ties.

In testimony whereof I affix my signature.

WILLIAM TATE BRADLEY.
